UNITED STATES PATENT OFFICE.

AUGUST FRANK YOUNG, OF BUNCETON, MISSOURI.

INDICATOR.

1,357,759.

Specification of Letters Patent. Patented Nov. 2, 1920.

Application filed August 31, 1917. Serial No. 189,213.

To all whom it may concern:

Be it known that I, AUGUST FRANK YOUNG, a citizen of the United States, residing at Bunceton, in the county of Cooper 5 and State of Missouri, have invented certain new and useful Improvements in Indicators; and I do hereby declare the following to be a full, clear, and exact description of the invention, such as will enable others skilled in 10 the art to which it appertains to make and use the same.

This invention relates to indicators, and more particularly to an indicator specially designed for use in railway cars for indicating to the passengers the names of the 15 streets or stations as they are approached.

An object of the invention is the provision of an indicator including a pair of rollers or shafts arranged one above the other and 20 an indicator cloth adapted to be moved back and forth between the rollers or shafts by the improved operating arms.

With these and other objects in view, the invention consists of the novel construction, 25 arrangement and combination of parts as will be hereinafter specifically described, claimed and illustrated in the accompanying drawings, in which:

Figure 1 represents a front elevation of 30 the indicator.

Fig. 2 represents a side elevation thereof, partly broken away.

Fig. 3 represents an enlarged detail view 35 of the spring actuated pawl and grooved pulleys, partly broken away.

Fig. 4 represents a side elevation of the spring actuated pawl and pulley, partly in section, and

Fig. 5 represents an enlarged detail view 40 of the driving mechanism for the lower shaft of the indicator.

Referring to the drawings in detail, wherein similar reference numerals designate corresponding parts throughout the 45 several views, the numeral 8 indicates a suitable base carrying vertically disposed standards 9 and a transversely directed top bar 10 having a substantially U shaped shaft support 11 secured at its web portion there- 50 to and having depending arms 12, supporting the outer ends of the top shaft 13 rotatably mounted in the arms 12 and in the vertical uprights or standards 9. Between the uprights 9 a sprocket wheel 14 is fixed 55 on the top shaft 13 and coöperates with a chain 15 working over a sprocket 16 on the

lower shaft 17 rotatably mounted between the standards or uprights 9. An indicator cloth 18 is secured at its opposite ends to the upper and lower shafts 13 and 17 between the uprights or standards 9 and is adapted to travel on and wind upon these shafts in the usual manner.

On one end of the top shaft 13 a ratchet wheel 19 having laterally projecting teeth is 60 fixed between one standard 9 and the adjacent arm 12 of the shaft support 11. A pulley 20 is rotatably mounted on the shaft 13 between the ratchet wheel 19 and the adjacent arm 12 of the supporting member 70 11 and is provided with two spaced grooves or channels 21 and 22. The pulley 20 and ratchet wheel 19 are retained in spaced relation by the upper end of a supporting bracket 23 having an aperture therein receiving the shaft 13 and provided with a pair of spaced arms or shoulders 24 and 38.

The bracket is secured at its lower end to the adjacent vertical standard or upright 9.

The pulley 20 is formed at its periphery 80 with a transversely directed recess 25 in which the pawl or locking member 26 is movable on a bolt 28. The member 26 is provided with a laterally projecting tooth 29 normally retained in engagement 85 with the teeth of the ratchet wheel 19 by the tension of a spring 30 coiled around the bolt 28 and disposed between the member 26 and the outer wall of the recess 25, as clearly shown in Fig. 3. One edge of the 90 tooth 29 is beveled at 31, whereby when said tooth is rotated with the pulley 20 and engages the inwardly curved upper end of the arm 24, it is automatically disengaged from the teeth of the ratchet wheel 19. 95 The pulley 20 is normally retained in the position illustrated in Figs. 1 and 2 by a coil spring 32 fixed at its lower end to the adjacent standard or upright 9 and secured at its upper end in the outer channel or 100 groove 21 of the pulley 20, as indicated at 23. An operating cord or cable 34 is fixed at one end to an eye or the like 35 fixed in the inner groove 22 of the pulley and extending downwardly over an idler pulley 105 36 fixed to the adjacent upright 9 and extended to a point conveniently near the motorman, engineer or conductor of the car, whereby when the cable or cord is pulled the pulley 20 is rotated in a counter clockwise direction. On its initial movement, the tooth 29 moves off of the end of the arm 24 110

and the spring 30 carries said tooth into locking engagement with the teeth of the ratchet wheel 19, thus rotating the pulley 20 and ratchet 19 in synchronism in one direction. The pulley 20 is rotated one-half of a revolution when stopped by the engagement of the tooth 29 with the end of the arm 38 of the bracket 28. The tension of the spring 32 carries the pulley back to its operative position after the cable 34 is released. It will be understood that while the shaft 18 is being rotated by the locking engagement of the tooth 29 with the ratchet wheel 19, the indicator cloth 18 is being wound upon the top shaft 13 and unwound from the lower shaft 17 traveling in the direction of the arrow, as indicated in Fig. 1.

When it is desired to move the indicator cloth 18 downwardly to wind upon the lower shaft 17, a second cable or cord 40 is actuated, which travels upon a pulley 41 rotatably mounted on the end of the shaft. The pulley 41 is retained in its normal position by a spring 42, and the pulley is provided with a tooth not shown, similar to the tooth 29 hereinbefore described and adapted to coöperate with the teeth of a second ratchet wheel 43 having the teeth directed oppositely from the teeth of the ratchet wheel 19, whereby when the operating cord 40 is pulled the pulley 41, ratchet wheel 43 and the shaft 13 are rotated in a direc-

tion opposite to that in which the shaft rotates when actuated by pulling the left hand cord or cable 34.

It will be understood that the indicator hereinbefore described is to be inclosed by a suitable casing having an opening through the top wall thereof covered by a plate of transparent material whereby the names of the streets, or stations marked on the indicator cloth 18 are clearly visible to the passengers of the car.

Having thus described the invention what is claimed as new is:

In an indicator, a support, a shaft carried by the support, a ratchet wheel mounted on the shaft, a pulley disposed adjacent said ratchet wheel, a pawl carried by said pulley and adapted to engage said ratchet wheel, a bracket carried by the support and having forked arms straddling said shaft and disposed between said pulley and said ratchet wheel, said pawl being normally retained out of engagement with said ratchet wheel by contact with one of said arms, the other of said arms being adapted to function as a stop for the pawl.

In testimony whereof I affix my signature in presence of two witnesses.

AUGUST FRANK YOUNG.

Witnesses:

H. E. MEEKER,
H. N. POPPER.
